UNITED STATES PATENT OFFICE

152,061

DESIGN FOR A BOTTLE DISPLAY FIXTURE

William I. Carr, Eldon, Mo.

Application October 6, 1947, Serial No. 141,763

Term of patent 3½ years

(Cl. D80—9)

To all whom it may concern:

Be it known that I, William I. Carr, a citizen of the United States, residing at Eldon, in the county of Miller and State of Missouri, have invented a new, original, and ornamental Design for a Bottle Display Fixture, of which the following is a specification, reference being had to the accompanying drawing, forming a part thereof.

Figure 1 is a front elevation of a bottle display fixture, showing my new design.

Fig. 2 is a side elevation of the bottle display fixture.

Fig. 3 is a plan view of the fixture.

I claim:

The ornamental design for a bottle display fixture, as shown.

WILLIAM I. CARR.
